UNITED STATES PATENT OFFICE.

WILHO A. KOSKEN, OF NEW YORK, N. Y., ASSIGNOR, BY MESNE ASSIGNMENTS, TO
BENJAMIN FARNHAM SMITH, OF CONCORD, MASSACHUSETTS.

TWISTER RING.

Application filed December 28, 1922. Serial No. 609,420.

To all whom it may concern:

Be it known that I, WILHO A. KOSKEN, a citizen of the Republic of Finland, residing at New York, in the county of New York and State of New York, have invented 5 new and useful Improvements in Twister Rings, of which the following is a specification.

This invention relates to twister rings of 10 the general type disclosed and claimed in my application Serial Number 599,638, filed November 8, 1922, for ring traveler and is 15 designed more particularly where a series of rings are employed for a single twister frame.

In the application above mentioned each 20 ring is supported by three bearing rollers. According to the present invention certain bearing rollers are designed to cooperate 25 with each of a pair of twister rings, so that while each ring is supported by three rollers, the total number of rollers is only two more than twice the number of rings, one of the extra two rollers being required for each 30 end ring of the series.

Further features of the invention relate 35 to tension devices by which the rotation of the rings may be retarded to regulate the tension on the strands, to means for cleaning 40 and oiling the rings, and to the means for taking up wear.

For a more complete understanding of 45 this invention, together with further objects and advantageous details and combinations 50 of parts, reference may be made to the accompanying drawings in which

Figure 1 is a fragmentary plan of a rail showing a plurality of twister rings carried thereby.

Figure 2 is a front elevation of the same.

Figure 3 is a section on line 3-3 of Figure 1.

Figure 4 is a detail section similar to a 45 portion of Figure 3, but showing a modification.

Referring first to Figures 1, 2, and 3, at 50 1 is indicated a rail for supporting a plurality of twister rings 2 arranged in series and rotatable in a common plane. Each 55 ring is supported above an opening 3 in the rail and spaced about the margin of this opening are three bosses, two being indicated at 4 and one of larger size at 5. The rail is perforated centrally of these bosses to receive oil cups, as shown at 6 and 7, and

supported by the rail are brackets 8, 9, and 10 for carrying shafts 11 depending within the oil cups. Journaled on these shafts are bearing rollers 12 and 13, the rollers 12, which are carried by the brackets 8, being 60 of larger diameter than the rollers 13 carried by the brackets 9 and 10. These rollers are spaced about the peripheries of the rings 2 substantially equally, and the rollers 12 are formed to engage the peripheries of a 65 pair of adjacent rings 2, while each roller 13 engages one ring only. Each roller has a depending sleeve portion 15 surrounding its respective shaft 11 and which extend beneath the surface of lubricant contained 70 in the cups 6 and 7 by which means these rollers are lubricated on their shafts in substantially the same manner as disclosed in the application above mentioned. Each roller 12 and 13 is also provided with a 75 peripheral groove having marginal flanges 16 which engage the top and bottom faces of the rings so that the rings are entirely supported thereby.

For the purpose of taking up wear between the various rings and rollers, the rollers 12 may be made adjustable with respect to the rings. For this purpose the shaft 11 carried by each bracket 8 passes through an enlarged opening 20 therein and 80 may be clamped in position relative to this opening by means of a nut 21 threaded on the upper end of the shaft and bearing against a washer 22 resting on the top of the bracket 8, a collar 23 being provided on the shaft 90 beneath the bracket 8 between which and the washer 22 the bracket may be clamped.

For the purpose of applying a drag to the rotation of the rings, as well as to clean the rings and to permit lubricant to be applied thereto, braking elements of fibrous material may be employed. As shown these elements or shoes are indicated at 25 and comprise pieces of felt of substantially 1 cross section which engage the outer faces of the 100 rings 2 and which are held in contact therewith by means of brake heads 26 which are mounted in pairs on resilient arms 27, one shoe being carried by each end of each arm and each arm being supported intermediate 105 its ends on the reduced extremity 28 of a screw pin 29 threaded through alternate brackets 8 and having at its outer end a screw driver slot 30 by which it may be turned. The reduced portion 28 of each pin 110

passes through a perforation 31 of the arm 27 which arm may rest against a shoulder 32 formed by a portion of larger diameter than the reduced extremity 28 as at 33. Surrounding this portion 33 and reacting between one face of the arm 27 and the head 34 of the screw is a coil spring 35. By adjustment of the screw the spring 35 may be moved inwardly against the rear face of the arm 27 until this arm contacts with the shoulder 32, whereupon further movement inwardly of the screw causes pressure to be exerted against the heads 26 to press the braking elements or shoes 25 into contact with the rings by the flexing of the arm 27. By this means the pressure of the braking elements against the ring peripheries may be adjusted as desired in accordance with the character of the yarn being twisted. The felt pad 25 not only exerts a retarding effect on the rotation of the rings, but also acts to clean the rings from foreign matter such as dirt or lint which may collect thereon in the operation of the machine. It also furnishes a means by which the bearing faces of the rings may be lubricated, it being found in practice that when no lubrication is employed the frictional resistance to the rotation of the rings changes with changes of humidity. By lubricating the rings, however, the effect of humidity is eliminated. For this purpose, therefore, each head 26 may be perforated as shown at 40 and through this perforation oil may be applied to the felt 25. While if desired oil may be applied to all the felts for the entire series of rings, if it is applied to one only it is transferred to all the rings of the series, since it is transferred from the nearest ring 2 through its bearing roller 12 to the next adjacent ring and from this ring through the other roller 12 bearing thereon to a succeeding ring and so on through the entire series.

In case it is desired to remove any of the rings this may be readily accomplished by removing the bracket 8 which carries the braking element operating thereon. To remove all the rings it is only necessary to remove every alternate roller 12 by removing those brackets 8 to which the spring arms 27 are fixed. The other rollers 12 need not be disturbed, as it will be noted that their brackets carry no braking elements since two of such elements are carried by the same roller bracket.

Each ring is provided with a suitable yarn eye, as indicated at 45, the eye shown being that described and claimed in the application above mentioned. As this is positioned entirely within the ring, lubricant from the shoes 25 is not liable to reach the yarn, especially since the centrifugal force due to the rotation of the rings tends to retain the oil on its outer periphery. If de-

sired, however, a construction shown in Figure 4 may be employed in which the ring 200 is made T shape in cross section, the stem of the T forming an outwardly extending annular flange 201 which fits between the roller flanges 16 midway of the top and bottom or end faces of the ring. These parts are so proportioned that the flanges 16 lie substantially flush with the top and bottom faces of the ring and centrifugal force tends to maintain the oil on the flange 201 and prevents it from passing over to the inside of the ring.

From the above description it will be seen that a plurality of rings may be properly supported for rotation with the number of rollers only two greater than the number of rings, each ring having a three point support, the rings rotating in a common plane; and also that the same elements not only serve as brakes to retard the rotation of the rings, but also as cleaning elements and lubricant applicators and that it is only necessary to apply lubricant to one of these elements to insure proper lubrication to the whole series.

Having thus described certain embodiments of this invention it should be evident to those skilled in the art that many changes and modifications might be made therein without departing from its spirit or scope as defined by the appended claims.

I claim:

1. In combination, a rail, a plurality of twister rings arranged in series on said rail, and a plurality of rollers journaled on said rail with their peripheries engaging the peripheries of said rings, certain of said rollers being positioned between a pair of rings and in engagement with both rings, and each of the remaining rollers engaging one ring only, the rollers engaging a pair of rings being of larger diameter than those engaging one ring only.

2. In combination, a rail, a plurality of twister rings arranged in series and rotatably carried by said rail, and bearing rollers engaging the peripheries of said rings, certain of said rollers engaging between adjacent pairs of rings and in contact with both rings of the pair, and certain of said rollers engaging one ring only, said rollers being spaced substantially equally about the periphery of each ring and the rollers engaging a pair of rings being of larger diameter than those engaging one ring only.

3. In combination, a pair of adjacent twister rings, bearings for said rings, and an arm having a braking element at each end, each element engaging one of said pair of rings.

4. In combination, a pair of adjacent twister rings, bearings for said rings, an arm having a braking element at each end, each element engaging one of said pair of

rings, and means for adjusting the pressure of said elements against their respective rings.

5. In combination, a series of twister rings, and bearings for said rings, including rollers between adjacent rings and against the peripheries of which said adjacent rings bear, said rollers being adjustable relative to said rings to take up wear.

10. 6. In combination, a pair of twister rings rotatable in a common plane, a spring arm having its ends positioned adjacent the peripheries of said rings, a brake head at each end of said arm, and a brake shoe carried by 15 each head and engaging the periphery of one of said rings.

7. In combination, a pair of twister rings rotatable in a common plane, a spring arm having its ends positioned adjacent the peripheries of said rings, a brake head at each 20 end of said arm, a brake shoe carried by each head and engaging the periphery of one of said rings, and means for adjusting said arm relative to said rings.

25. 8. In combination, a rotatable twister ring, a braking and cleaning element for said ring comprising a piece of absorbent material, and means for pressing said absorbent material against the periphery of said ring.

30. 9. In combination, a rotatable twister ring, a braking and cleaning element for said

ring comprising a holder and a piece of absorbent material in said holder, and means for pressing said absorbent material against the periphery of said ring, said holder having an opening therein through which lubricant may be applied to said absorbent material.

35. 10. In combination, a pair of adjacent twister rings, bearings for said rings including a roller engaging the periphery of both rings, and a pad of absorbent material adapted to contain a lubricant thrust against one of said rings, whereby lubricant may be transferred from said ring by said roller to 40 the other of said rings.

45. 11. In combination, a series of twister rings, bearings for said rings including rollers between adjacent rings and against the peripheries of which said adjacent rings bear, and means for applying a lubricant to the periphery of one of said rings to be 50 spread by said rollers to the other rings.

55. 12. In combination, a series of rotatable twister rings, means for applying a lubricant to the periphery of one of said rings, and means for transferring lubricant from said one ring to the other rings of the series.

In testimony whereof I have affixed my signature.

WILHO A. KOSKEN
